MAKING COVERED THREADS

**Aaron Rosenstein, New York, and Harry Dolan,
Brooklyn, N. Y., assignors to Rosenstein Bros.,
New York, N. Y., a firm**

Application September 10, 1942, Serial No. 457,843

3 Claims. (Cl. 18—8)

This invention relates to the art of making covered elastic threads.

Heretofore, the winding of textile threads upon a core consisting of rubber or other elastic material for the purpose of providing a covered elastic thread, was a fairly complicated procedure requiring expensive machinery and considerable time.

An object of the present invention is to simplify this procedure and to provide a method of winding textile threads upon an elastic thread which does not require expensive installation and which is quick and simple.

Another object is to improve the covering of elastic threads and other elongated objects through the use of extruded thread for this purpose.

A further object is to improve the structure of covered elastic threads and to simplify their manufacture by combining in the course thereof the extrusion of elastic threads with that of the covering.

Other objects of the present invention will become apparent in the course of the following specification.

In accomplishing the objects of the present invention it was found desirable to extrude continuously a non-elastic thread and to wind it continuously as it is being extruded upon an elastic thread or other elongated object. The winding is accomplished by rotating the spinneret, the coagulating tank, the extrusion opening or nozzle, or the elastic thread. The formation of an elastic thread may take place at the same time as the covering thread is being extruded. Two or more rotary spinnerets or tanks may be used for winding different extruded threads upon an elastic core.

The invention will appear more clearly from the following detailed description when taken in connection with the accompanying drawings showing, by way of example, preferred embodiments of the inventive idea.

In the drawings:

Figure 1 is a diagram illustrating a process of extruding a thread and winding it upon a rubber thread;

Figure 2 is a section through a spinneret;

Figure 3 is a diagram illustrating the finished covered elastic thread;

Figure 4 illustrates diagrammatically a process combining two separate extrusions for the making of a covered elastic thread;

Figure 5 illustrates diagrammatically the mak-

ing of a rubber thread carrying two oppositely wound extruded threads;

Figure 6 illustrates diagrammatically an elastic thread carrying two extruded threads wound in opposite directions.

Figure 7 illustrates diagrammatically an apparatus wherein a spinneret is rotated around an elastic thread.

Figure 8 illustrates diagrammatically an apparatus wherein a spinneret carries out a planetary movement.

Figure 9 is a section along the line 9—9 of Figure 8.

Figure 10 is a diagram illustrating an apparatus wherein an elastic thread is rotated around a spinneret.

Figure 11 is a top view of the apparatus shown in Figure 10.

Figure 12 is a diagram illustrating a viscose spinning operation combined with the winding operation.

The process illustrated in Figure 1 of the drawings includes the manufacture of rayon from wood pulp or other supply of cellulose by the viscose method or any other suitable method known in the art.

The cellulose mixture after having been properly aged in an accustomed manner, is forced by a suitable pump 10 from a pipe 11 and through a pipe 12 and into the usual candle filter 13. Thence the mixture flows through a pipe or glass tube 14 and into a hollow stationary ring 27 which surrounds a rotary tank 17. The tank 17 carries a nozzle or spinneret 15 usually formed of noble metals, glass or the like. The nozzle 15 is in communication with the interior of the ring 27 and is provided with one or more orifices through which the cellulose mixture or viscose is forced into a coagulating bath 16 situated in the tank 17. Obviously, the nozzle 15 is rotated along with the tank 17 while remaining in communication with the interior of the ring 27. The coagulating bath is prepared in the usual manner and may contain sulphuric acid and other sulphate or sulphite salts. The cellulose mixture leaves the bath 16 in the form of a thread 18 through a narrow opening provided in a bottom portion 19 of the tank 17.

The tank 17 and the nozzle 15 carried by the tank are rotated by any suitable means, such as a pulley 20 and an endless belt 21. A tube 23 which extends through the center of the tank may be carried by the bottom portion 19.

An elastic thread 24 is drawn through the tube 23 by any suitable means not shown in the draw-

lings. The elastic thread 24 passes between rollers 25 as it is being unwound from a spool 26.

The extruded thread 18 is pulled against the elastic thread 24 in such manner that it will wind itself spirally around the elastic thread 24 due to the rotation of the tank portion 19 and the feed movement of the elastic thread 24. Thus a covered elastic thread is produced, which is shown in Figure 3 and which comprises an elastic core 24 and an extruded covering 18 wound upon the core 24.

Obviously, rayon thread 18 may be substituted by any suitable extruded thread.

Figure 2 shows a device which may be used when a thread 18 is extruded directly into the open through an extrusion opening 30 of a bottom portion 31 of a spinneret 32. A suitable solution 33 of any soup of proper viscosity is introduced in the usual manner into the spinneret 32 through a pipe 34 which is attached to the upper immovable portion 35 of the spinneret. The portion 35 is attached to supporting plates 36 and carries a threaded flange 37 which meshes with a nut 38. A packing 39 is situated between the flange 37 and the nut 38 and is in engagement with a rotary tube 40 which extends through the spinneret and which may be integral with the rotary bottom portion 31 of the spinneret.

The rotary portion 31 may be conveniently designated as the spinneret, while the immovable portion 35 may be designated as the tank.

The spinneret portion 31 is firmly connected with a pulley 41 which is driven by an endless belt 42. The portion 31 is held in place by the engagement of a flange 43 of the portion 31 with a nut 44 which is screwed upon a threaded flange 45 of the portion 35. A packing 46 is situated between the flanges 43 and 45.

In operation, a suitable solution 33 is supplied to the spinneret 32 through the pipe 34, and a thread 18 is extruded through the opening 30 of the spinneret portion 31. A rotation of the endless belt 42 passing over the pulley 41 will rotate the spinneret portion 31. At the same time, an elastic thread 24 is drawn through the tube 40. Since the opening 30 rotates around the elastic thread 24, the extruded thread 18 may be conveniently wound upon the elastic thread to form the covered elastic thread illustrated in Figure 3.

Any suitable elastic thread 24 may be used for the purpose of the present invention; it may consist of rubber, balata, gutta-percha, synthetic rubber and other extensible and elastic materials. The manufacture of the elastic thread may constitute an integral part of the described method, as indicated in Figures 4 and 5.

Figure 4 shows a container 50 which is suspended from a supporting plate 51 and which may be filled with liquid rubber latex 52 through a pipe 53.

Obviously, rubber latex of the common Hevea variety may be substituted by any analogous dispersions of rubber, synthetic rubber and similar materials in a vulcanized or unvulcanized condition. The dispersions may be concentrated, thinned, stabilized or otherwise preliminarily treated and may contain any desirable compounding and conditioning agents.

The container 50 is preferably steam heated by any suitable means (not shown). A rubber thread 24 is extruded through an opening 54 provided in the bottom of the container 50. This rubber thread may be washed and dried, whereupon it is taken to a vulcanizer and properly

cured in the customary manner (not shown) before it is introduced into the pipe 40 of the spinneret 32.

As the rubber thread 24 leaves the tube 40, a thread 18 which is extruded through the opening 30 of the spinneret 32 is wound upon the rubber thread in the previously described manner.

An important advantage of this process is that since a freshly extruded rubber thread retains some of its adhesiveness, it is permanently and firmly connected with its covering constituted by the extruded thread 18.

Figure 5 illustrates a process of making a covered elastic thread shown in Figure 6 and comprising an extruded thread 60 which is wound in the opposite direction to that of the extruded thread 18 carried by the elastic core 24.

The elastic thread 24 is extruded through the container 50 and is passed through the tube 40 of the spinneret 32, whereupon a thread 18 extruded through the spinneret 32 is wound upon the elastic thread 24. The bottom portion 31 of the spinneret 32 is rotated by the belt 42 and the pulley 41 in the direction of the arrow 61. Since the freshly extruded rubber thread 24 is still adhesive, while the freshly extruded thread 18 is somewhat plastic, a very permanent and firm connection is provided between the elastic core 24 and the covering 18.

The covered thread is passed immediately thereafter through a tube 140 of another spinneret 132, which is similar to the spinneret 32 and the bottom portion 131 of which is rotated by a belt 142 and a pulley 141 in the direction of the arrow 62 which is opposed to the direction of rotation of the belt 42 and the pulley 41. Thus the thread 60 extruded through the spinneret 132 is wound upon the covered elastic thread emerging out of the tube 140 in a direction opposite to that in which the thread 18 was wound.

Figure 7 illustrates an apparatus wherein a spinneret 70 is rotated about an elastic thread 24 in order to wind a plurality of extruded threads 18 upon the thread 24. The spinneret 70 is connected by an arm 71 with a toothed ring 72 which is mounted upon a stationary supporting ring 73 and which meshes with a pinion 74. A so-called soup is supplied to the spinneret 70 through a stationary pipe 75 which is mounted in the ring 73 and which is in communication with a tubular member 76 constituting a part of the rotary spinneret. The soup is extruded through the openings 30 of the spinneret in the form of threads 18. The elastic thread 24 extends through a central opening provided in the supporting ring 73. The spinneret 70 is rotated around the elastic thread 24 by the pinion 74 which transmits its rotation to the toothed ring 72 carrying the spinneret 70 by means of the arm 71. Thus the extruded threads 18 are wound upon the elastic thread 24.

In the construction shown in Figures 8 and 9, a spinneret 88 rotated about an elastic thread 24 is provided with a rotary bottom portion 80 which is suspended from an upper portion 81 by an annular nut 85 carried by the flange 82 of the portion 81 and supporting a flange 83 of the rotary portion 80. The portion 80 carries a gear wheel 84 which meshes with a stationary gear crown 86 carried upon a tube 87. The tube 87 is mounted in the supporting ring 73 and contains the elastic thread 24. The spinneret 88 is rotated by the pinion 74 meshing with the toothed ring 72 which is carried by the supporting ring 73 and which carries the spinneret by means of the arm 71.

As in the previously described construction, a soup is supplied to the spinneret 88 through the stationary pipe 75 and a pipe 76 rotating along with the spinneret. The spinneret is rotated around the elastic thread 24 by the pinion 74 which meshes with the toothed ring 72. At the same time, the bottom portion 80 is rotated around its axis by the engagement of the gear wheel 84 with the gear crown 86. Thus the spinneret portion 80 carries out a planetary movement about the elastic thread 24. The thread 18 extruded through a central opening 30 of the spinneret is somewhat twisted as it is being wound upon the elastic thread 24, due to this planetary motion of the spinneret portion 80.

Figures 10 and 11 illustrate an apparatus wherein the elastic thread 24 is rotated around a spinneret 90 which is stationary. The soup is introduced through a pipe 91 and the thread 18 is extruded through a bottom opening 30. The elastic thread 24 extends through openings provided in two rotary arms 92 and 93 joined by a rod 94. The arm 92 is firmly connected with a gear wheel 95 meshing with a pinion 96. The arm 93 extends around the spinneret and is supported by an annular flange 97 which is firmly connected with the spinneret.

The thread or similar elongated element 24 is rotated about the spinneret 90 by a pinion 96 which rotates the wheel 95 connected to the arm 92. At the same time, a thread 18 is extruded through the opening 30, so that it is wound upon the thread or element 24.

Figure 12 illustrates an apparatus for carrying out a viscose spinning operation. The viscose solution flows through a filter 100 and a pipe 101 into a spinneret 102 having a stationary portion 103 and a rotary portion 104 which is supported by an annular nut 105 carried by a flange 106 of the portion 103 and carrying a flange 107 of the portion 104. The spinneret portion 104 is rotated by a pulley 108 and a belt 109. The portion 104 carries a tube 110 for an elastic thread 24 and is immersed in a coagulating bath 111 contained in a tank 112. The extruded thread 18 is wound upon the elastic thread 24 and the two threads are passed over guides 113 and 114 and over a godet or revolving draw-wheel 115. Thence the covered elastic thread passes through a funnel guide 116 and into the usual centrifugal pot or spinning box 117.

It is apparent that the specific illustrations shown above have been given by way of illustration and not by way of limitation and that the

methods and apparatus above described are subject to wide variation and modification without departing from the scope or intent of the present invention. All of such variations and modifications are to be included within the scope of the present invention.

What is claimed is:

1. The method of producing an elastic yarn having an inelastic cover which comprises continuously extruding a non-elastic cover thread from a solution, moving an elastic core thread in the general direction of its length and in a path past the extrusion point of the non-elastic thread in which it is maintained out of contact

15 with the solution, and moving the freshly extruded non-elastic thread at a point adjacent its point of extrusion in a path of revolution about the elastic core thread to wind it continuously in a plastic state as it is being extruded 20 directly upon the surface of the elastic core thread.

2. The method of producing an elastic yarn having an inelastic cover which comprises the steps of continuously extruding an elastic core 25 thread from a solution, substantially simultaneously extruding a non-elastic thread from a solution, moving the elastic thread as extruded in the general direction of its length and in a path past the extrusion point of the non-elastic

30 thread, and moving the non-elastic thread while in a plastic and sticky state in a path of revolution about the elastic thread while the latter is still in a sticky state to wind the non-elastic 35 thread about the elastic thread and to cause their adherence together.

3. An apparatus for producing an elastic yarn having an inelastic cover, said apparatus comprising, in combination, means having an extrusion opening for continuously extruding an elastic core thread from a solution, other means having an extrusion opening for substantially

40 continuously extruding a non-elastic thread from a solution, means for continuously moving the elastic thread as extruded 45 in the general direction of its length and in a path past the extrusion point of the non-elastic thread, and means continuously moving the non-elastic thread while in a plastic and sticky state in a path of revolution about the elastic thread

50 while the latter is still in a sticky state to wind the non-elastic thread about the elastic thread and to cause their adherence together.

AARON ROSENSTEIN.
HARRY DOLAN.
